US00D996415S

(12) **United States Design Patent** (10) **Patent No.:** **US D996,415 S**
(45) **Date of Patent:** ** *Aug. 22, 2023

(54) **NOTEBOOK COMPUTER**

(71) Applicant: **LG ELECTRONICS INC.**, Seoul
(KR)

(72) Inventors: **Heechang Lee**, Seoul (KR); **Junghyun Min**, Seoul (KR)

(73) Assignee: **LG ELECTRONICS INC.**, Seoul
(KR)

(*) Notice: This patent is subject to a terminal disclaimer.

(**) Term: **15 Years**

(21) Appl. No.: **35/512,852**

(22) Filed: **May 3, 2021**

(80) **Hague Agreement Data**

Int. Filing Date: **May 3, 2021**

Int. Reg. No.: **DM/214182**

Int. Reg. Date: **May 3, 2021**

Int. Reg. Pub. Date: **Nov. 5, 2021**

(30) **Foreign Application Priority Data**

Nov. 27, 2020 (KR) 30-2020-0058241

(51) **LOC (14) Cl.** **14-02**

(52) **U.S. Cl.**

USPC **D14/315**; D14/327

(58) **Field of Classification Search**

USPC D14/315-327, 341-346, 487-389;
D24/160, 185-186; D21/324, 329-330,

(57) **CLAIM**

The ornamental design for a notebook computer, as shown and described.

DESCRIPTION

1. Notebook Computer

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

(Continued)

Reproductions 1.1 to 1.7 show the notebook computer in a folded state of use, whereas reproductions 1.8 to 1.14 show the notebook computer in an unfolded state of use.

1 Claim, 14 Drawing Sheets

(58) Field of Classification Search

USPC D21/332, 515; D18/1-2, 4.1-4.6,
D18/12.2-12.3
CPC G06F 1/1681; G06F 1/16; G06F 1/1616
See application file for complete search history.
